EARPHONE RECORDING SYSTEM

Herman S. Heller, West Los Angeles, Calif.

Application January 24, 1941, Serial No. 375,807

15 Claims. (Cl. 179—6)

This invention relates to radio receiving systems, particularly in situations wherein the operator is furnished with radio head phones, and wherein a recording is made of received signals, the general purpose and accomplishment of the invention being the provision of means for indicating on such a record any period or periods during which the head phones are not worn by the operator.

The invention is generally designed for application in such situations as aircraft service, in which it is highly important that one or more radio operators be constantly on watch, and in which it is highly important that any failure on the part of the operator or operators be made known to supervisory authorities.

The present invention meets this need by the provision of means for recording on the record medium, along with the incoming communication signal, a current wave of predetermined frequency or other distinguishable character. This indication current is produced and recorded at all times that the head phones are not being worn. When the head phones are positioned on the head of the operator, however, a switch associated with the phones is automatically actuated to stop the recording of the indication current, so that only the received communication signal is then recorded. Subsequent analysis of the record reveals whether or not the operator was listening during the reception of, for example, instructions transmitted from the control station. As it is common in aircraft service to have more than one individual on "listening duty" simultaneously, for instance, the pilot and co-pilot, or pilot and radio operator, the invention provides means for producing one characteristic current wave for each head phone set, which is recorded along with the received communication signal when the head phones are not being worn, with switching means in association with each head phone set for interrupting the recording of the corresponding current wave when that set is on the head of the operator. The resulting record discloses whether either or both of the operators was on duty at any given time, and allows responsibilities to be accurately placed.

The invention will be understood from the following detailed description of certain selected illustrative embodiments thereof, reference for this purpose being had to the accompanying drawings, in which:

Fig. 1 is a diagrammatic view of one illustrative system in accordance with the invention;

Fig. 2 is a modification of Fig. 1;

Fig. 3 is a diagrammatic plan view of a portion of the recording tape and recording magnets of the form of the invention of Fig. 2;

Fig. 4 shows a further modified form of the invention;

Fig. 5 is a sectional view of an earphone device in accordance with the invention, the section being taken in accordance with line 5—5 of Fig. 6;

Fig. 6 is a section taken on line 6—6 of Fig. 5;

Fig. 7 is a perspective of a contact device used in the earphone;

Fig. 8 is a view similar to Fig. 5, but showing a modification, the section of Fig. 8 being on line 8—8 of Fig. 9; and

Fig. 9 is a section taken on line 9—9 of Fig. 8.

The illustrative forms of the invention contemplate two sets of head phones, one for the pilot and one for the co-pilot or radio operator. It is to be understood, however, that this is not limitative on the invention, since one head phone set or any greater number may be provided, as will be evident.

In Fig. 1 of the drawings, two head phone sets 10 and 11 are indicated, each comprising a pair of earphones 12. Numeral 13 designates a radio receiving set, to the output terminals of which are connected leads 15 and 16 going to recorder 17. The recorder 17 may be of any suitable type, though it is preferably and here indicated as of the magnetic tape type, comprising a magnetic tape 18 travelling between reels 19 and 20, and acted on by translating magnets 21 connected to leads 15 and 16. Tape 18 is constantly driven, and receives a continuous record of all communication signal currents delivered from receiver 13 to leads 15 and 16.

Head phone sets 10 and 11 are connected by leads 25 and 26, respectively, to communication signal lead 16 and by leads 27 and 28 to the stationary contact arms 29 and 30 of relays R₁ and R₂, respectively. The other communication signal lead 15 is connected by leads 30 and 31 to the intermediate, movable spring contact arms 32 and 33 of relays R₁ and R₂, respectively. Contact arms 32 and 33 normally make with stationary contact arms 34 and 35, respectively. The relays R₁ and R₂ have electromagnets 36 and 37, respectively, which when energized move the intermediate spring contact arms 32 and 33 out of contact with arms 34 and 35, and into contact with arms 29 and 30, respectively. Thus energization of magnet 36 connects head phones 10 across communication signal circuit 15, 16, and energization of magnet 37 connects head phones 11 across circuit 15, 16.

Magnets 36 and 37 are energized through switches S₁ and S₂ contained in head phone sets 10 and 11, which switches are automatically closed as the head phones are positioned on the head of the operator. Suitable automatically operated switch means are embodied in the head phone devices shown in Figs. 5 to 9, and will be described in detail hereinafter. A source of current for magnets 36 and 37 is indicated at 40. Leads 41 connect one side of this source of current to head phone switch contacts 42, and the cooperating head phone switch contacts 44 are connected by leads 45 to the magnets 36 and 37. Return leads 46 from magnets 36 and 37 are connected to the other side of current source 40. It will be evident that closure of either switch S₁ or switch S₂ will result in energization of the corresponding relay magnet, which will in turn connect the corresponding earphone set across communication signal circuit 15, 16.

The stationary relay contacts 34 and 35 are connected to communication signal circuit lead 16 by circuit leads 50 and 51, and as here shown, said leads contain circuit elements through which indication signal currents are introduced thereto. Thus, in the specific arrangement of Fig. 1, circuit leads 50 and 51 contain the secondary windings 52 and 53 of coupling transformers T, which have their primary windings 54 and 55 connected to the output terminals of generators 56 and 57, respectively. Generators 56 and 57 may typically be vacuum tube oscillators of conventional design. Oscillators 56 and 57 will, however, preferably be designed to generate currents of sufficiently different frequencies as to be readily distinguishable. For instance, both may generate frequencies in the audio range, but the frequency of one may typically be twice the frequency of the other. Of course, any expedient other than the use of oscillators having different frequencies may be employed for the purpose of generating two readily distinguishable current waves, the purpose of the generators 56 and 57 being simply to introduce to circuits 50 and 51 two currents which may be recorded by recorder 17, and which are readily distinguishable upon subsequent audible reproduction.

As previously explained, the contact arms 32 and 33 of relays R₁ and R₂ stand normally in contact with arms 34 and 35, respectively. At such time, the output currents delivered from oscillator 56 and 57 are connected through circuits 50, 53 and 51, 52, respectively, across signal current circuit 15, 16, and hence flow in the latter to recording magnets 21 of recorder 17 and are recorded on magnetic tape 18. The oscillator currents from both oscillators 56 and 57 as well as any communication signal current delivered from radio receiver 13 will thus flow in circuit 15, 16 and in magnets 21. The record on tape 18 accordingly consists of the communication signal, with the two oscillator waves superimposed thereon. Upon subsequent reproduction, the two oscillator waves will be distinguishable from the communication signal, being recognizable, for instance, as two tones of different pitches. The presence of both tones of course indicates that neither head phone set was in use. If on reproduction, but one of the oscillator tones is heard, the meaning is that the corresponding head phone set was not in use, but that the other head phone set was in use. Thus it is known that but one operator was on duty, and it is known which head phone set (that of the pilot, or of the co-pilot or radio operator) was being used. And if

neither oscillator tone is present on reproduction of the record on tape 18, it is known that two operators were on duty, both head phone sets having been in service at the time in question.

Figs. 2 and 3 show a modification, in which separate records are made of the oscillator and communication signals, as distinguished from the superimposed records made by the system of Fig. 1. Corresponding parts in Figs. 1 and 2 are identified by like reference numerals. In Fig. 2, radio receiver output leads 15 and 16 go to translating magnets 21 of recorder 17, the same as in Fig. 1. However, the two oscillator tones are recorded by means of separate pairs of translating magnets 60 and 61, the three pairs of translating magnets 21, 60 and 61 being spaced transversely of the record tape (see Fig. 3) so as to make three recordings on three adjacent, longitudinally extending lanes of the tape. In Fig. 2, circuit leads 50 and 51, instead of being connected to communication signal circuit 15, 16, are connected to leads 63 and 64, going to one side of the windings of electromagnets 60 and 61, respectively. The other sides of the windings of said electromagnets 60 and 61 are connected by leads 65 and 66 to the arms 32 and 33 of relays R₁ and R₂, respectively.

The operation of the system of Figs. 2 and 3 is the same as that of Fig. 1, excepting only that oscillator output currents are delivered to circuits 63, 65 and 64, 66, to be recorded as separate records on the tape, rather than to the circuit 15, 16 to be recorded along with the communication signal, as in Fig. 1.

Fig. 4 is a still further modification, in which the two oscillator currents are recorded as separate records on laterally spaced lanes of the tape, the same as in Figs. 2 and 3, but in which the communication signal current, instead of being recorded as a third individual record, is superimposed on both oscillator records. Thus, as shown in Fig. 4, the circuit 15, 16 is connected by leads 70 and 71 across circuits 63, 65 and 64, 66. Accordingly, circuit 63, 65 and magnet 60 will carry the oscillator current from oscillator 56, as well as any communication signal current present, while the circuit 64, 66 and magnet 61 will carry the oscillator current from oscillator 57, as well as any communication signal current present. Two records are thus produced, side by side, each containing a record of incoming communication signals, as well as the record of an oscillator wave throughout all periods that the corresponding head phone set was not in use.

In all of the above described systems, reproduction of the record or records obtained as described enables accurate ascertainment of what communication signals were received by the aircraft throughout the flight, as well as ascertainment of whether the operators of the aircraft were properly "listening in" at all times, or during the reception of any particular communication. Besides the valuable information to be gathered from the record, for instance in the event of a mishap and the desire to ascertain if certain instructions were duly received, the positive check on the operators provided by the system is strongly conducive to proper attention to duty.

In the illustrative forms of the invention, the oscillator currents are recorded during periods of non-use of the earphones, stretches along the record devoid of the oscillator record denoting periods of use of the earphones. Of course, this relationship may be reversed; and whether the presence or absence of oscillator signal on the

record tape corresponds with use of the earphones, the record as a whole may be regarded as a record indicating periods of use of the earphones.

Figs. 5, 6 and 7 show an earphone device equipped with an automatically actuated switch, in accordance with the invention. Numeral 80 designates generally the metal case of a conventional earphone, the forward wall 81 of which is formed with usual perforations 82 designed to permit entrance of sound waves. Secured as by rivets 83 to the front face of wall 81 is a mounting ring 84, an insulation ring 85 preferably being placed between ring 84 and wall 81. Mounted on ring 84 is a switch device generally designated by numeral 86. As here embodied, this switch device includes three pairs of contacts 87 and 88 circularly spaced about ring 84 (see Fig. 7). The contact 88 of the first pair is mounted on a conductive arm 89 secured to ring 84. Contact 88 faces away from ring 84, in opposition to inwardly facing contact 87. The latter is mounted on one end of a flat spring 92, secured at the center to ring 84, as by means of rivet 93. The other end of spring 92 carries the outwardly facing contact 88 of the next pair of contacts, and opposed to said contact 88 is a contact 87 carried by one end of a flat spring member 95 similar to spring member 92, member 95 being mounted on ring 84 as by means of rivet 96. Spring member 95 carries at its opposite end outwardly facing contact 88, which is opposed by inwardly facing contact 87 mounted on spring arm 97 secured to ring 84 as by rivets 98. Electrical connections 99 and 100 are made to members 90 and 97, respectively, as shown in Fig. 6. The contacts 87 and 88 are normally spaced apart. Inward pressure on the spring contact arms carrying the inwardly facing contact 87 causes contact to be made between the several pairs of contacts 87, 88, and therefore completes the circuit from connection 99 to connection 100. Such inward pressure is automatically effected when the earphone is pressed against the ear of the operator.

As shown in Figs. 5 and 6, the earphone case 80 is surrounded by a soft rubber jacket 102, which has at the front a flexible wall or earpiece portion 103 having at the center an aperture 104 adapted to admit the sound waves, wall 103 being arranged to overlie and to normally come immediately adjacent the spring carrying arms for the movable contacts 87. Jacket 102 fits the periphery of case 80 closely, except at the bottom, where space is provided for conductors, and fits the back of the case closely except for an enlargement 105, designed to accommodate earphone terminals 106, connections 107 leading from the latter out an aperture 108 at the bottom, and connections 109 for the other earphone of the set leading out an aperture 110 at the top of the enlargement 105.

When the earphone is pressed against the ear of the operator, the flexible wall 103 is deflected inwardly, and depresses contacts 87 against contacts 88, thus closing the circuit from connection 99 to connection 100. The provision of the three pairs of contacts 87, 88 necessitates proper positioning of the earphones on the head of the wearer, as otherwise all three pairs of contacts will not be closed, and the circuit will remain open. The operator will know when the earphones are properly positioned and all three pairs of contacts are closed by reason of the fact that at such time the earphones become connected

to the output of the radio receiver. Thus the phones will remain "dead" if they are not in proper position at the ears of the operator.

Figs. 8 and 9 show a modification. The receiver case 80 is the same as in Figs. 5 and 6. Case 80 is enclosed by an exterior case 130 comprising a peripheral member 131 and a back member 132. Back member 132 has an annular flange 133 received tightly inside peripheral member 131 and abutting a rearwardly facing shoulder 135 on case 80, a rubber washer 137 preferably being placed between flange 133 and shoulder 135.

Peripheral member 131 has, forwardly of case 80, a bore 140 which slidably receives an outwardly extending annular flange 141 on an earpiece plunger 142, the latter having an annular portion 143 slidable within reduced bore 144. The rearwardly facing shoulder at 145, between bores 140 and 144, serves as a stop to outward movement of the plunger. Plunger 142 has apertures 150 at the center, to admit sound waves, and has mounted on its inner face 151, around apertures 150, a switch contact means 86 which is preferably and here shown as of the same nature as that illustrated in Fig. 7, and is therefore identified by corresponding reference numerals. The mounting ring 84 in this instance is secured to the face 151, and the spring members bearing the contacts 87 come adjacent an insulation ring 160 secured to the front face of case 80. When the earphone as thus described is pressed to the ear, the plunger 142 is depressed, or moved inwardly relative to member 131 and case 80, the spring arms carrying the contacts 87 being prevented from inward movement by the case 80, and the contacts 88 accordingly closing against them to complete the circuit between connections 99 and 100, as before.

It will be understood that the drawings and description are for illustrative purposes only, and that various changes in design, structure and arrangement may be made without departing from the spirit and scope of the invention or of the appended claims.

I claim:

1. In a system of the character described, the combination of a circuit for communication signal currents, an earphone arranged to receive signal currents from said circuit, and means controlled by positioning said earphone at the ear of an operator for making a record indicating periods of use of said earphone.

2. In a system of the character described, the combination of a circuit for communication signal currents, an earphone arranged to receive signal currents from said circuit, and means controlled by pressing said earphone against the ear of an operator for making a record indicating periods of use of said earphone.

3. In a system of the character described, the combination of a circuit for communication signal currents, a phone arranged to receive signal currents from said circuit, means for producing an indication current whose flow is controlled in accordance with use of the phone, and means for making a time record on a traveling record medium of said indication current in a manner to indicate periods of use and non-use of said earphone.

4. In a system of the character described, the combination of a circuit for communication signal currents, an earphone arranged to receive signal currents from said circuit, means for pro-

- ducing and recording an indication current, and means controlled by positioning said earphone at the ear of an operator for interrupting recording of said indication current.
5. In a system of the character described, the combination of a circuit for communication signal currents, an earphone arranged to receive signal currents from said circuit, and means for making on a traveling record medium of a record of signal currents and a record indicating periods of use of said earphone.
6. In a system of the character described, the combination of a circuit for communication signal currents, an earphone arranged to receive signal currents from said circuit, means for producing an indication current, and means for continuously recording communication signal currents, and for recording said indication currents during times indicating periods of use of said earphone.
7. In a system of the character described, the combination of a circuit for communication signal currents, an earphone arranged to receive signal currents from said circuit, means for producing an indication current, and means for continuously recording communication signal currents, and for recording said indication currents during periods of non-use of said earphone.
8. In a system of the character described, the combination of a circuit for communication signal currents, an earphone arranged to receive signal currents from said circuit, means for producing an indication current, and means for making a composite record of communication signal currents, and of said indication current during times such as will indicate periods of use of said earphone.
9. In a system of the character described, the combination of a circuit for communication signal currents, an earphone arranged to receive signal currents from said circuit, means for producing an indication current, and means for making a composite record of communication signal currents, and of said indication current during times of non-use of said earphone.
10. In a system of the character described, the combination of a circuit for communication signal currents, a plurality of earphone devices arranged to receive signal currents from said circuit, means for producing a corresponding plurality of indication currents of different characteristics, and means for continuously recording communication signal currents, and for recording said indication currents during times indicating periods of use of the respective earphone devices.
11. In a system of the character described, the combination of a circuit for communication signal currents, a plurality of earphone devices arranged to receive signal currents from said circuit, means for producing a corresponding plurality of indication currents of different frequency characteristics, and means for continuously recording communication signal currents, and for recording said indication currents during times indicating periods of use of the respective earphone devices.
12. In a system of the character described, the combination of a circuit for communication signal currents, an earphone, current producing means for producing an indication current, a recorder for recording electrical currents, means normally connecting said current producing means to said recorder, and means automatically operable while said earphone is positioned at the ear of an operator for disconnecting said current producing means from said recorder.
13. In a system of the character described, the combination of a circuit for communication signal currents, an earphone device, a switch on said earphone device automatically closed when said earphone device is pressed to the ear of an operator, a source of electrical current of predetermined characteristics, a recorder for electrical currents, electric circuiting normally connecting said source of current of predetermined characteristics to said recorder, and circuiting operating when said earphone switch is closed to connect said earphone device to said communication signal circuit and to disconnect said source of current from said recorder.
14. In a system of the character described, the combination of a circuit for communication signal currents, an earphone device, a switch on said earphone device automatically closed when said earphone device is pressed to the ear of an operator, a source of electrical current of predetermined characteristics, a recorder for electrical currents receiving electric currents from said communication signal circuit, electric circuiting normally connecting said source of current of predetermined characteristics to said recorder, and circuiting operating when said earphone switch is closed to connect said earphone device to said communication signal circuit and to disconnect said source of current from said recorder.
15. In combination with an earphone device having a case, a switch mounted on said case, and a jacket for said case including a centrally perforated flexible compressible wall at the inner side of said case forming an ear piece adapted to be engaged and depressed by the ear of a listener and to operate said switch means by such depression.

HERMAN S. HELLER.

CERTIFICATE OF CORRECTION.

Patent No. 2,342,667.

February 29, 1944.

HERMAN S. HELLER.

It is hereby certified that error appears in the printed specification of the above numbered patent requiring correction as follows: Page 4, first column, line 9, claim 5, for "of" read --both--; and that the said Letters Patent should be read with this correction therein that the same may conform to the record of the case in the Patent Office.

Signed and sealed this 16th day of May, A. D. 1944.
